[76] Inventor: Clayton A. Elliott, 1931 Arbor La.,
Union, N.J. 07083

Primary Examiner—Bruce W. Dunkins
Attorney, Agent, or Firm—Martha G. Pugh

[**] Term: 14 Years

[57] **CLAIM**

[21] Appl. No.: 740,773

The ornamental design for an adjustable drawer unit or
similar article, as shown and described.

[22] Filed: Nov. 11, 1976

DESCRIPTION

[51] Int. Cl. ..... D6—04

FIG. 1 is a front elevational view of an adjustable
drawer unit or similar article showing my design;

[52] U.S. Cl. D6/159; D6/166;

FIG. 2 is a side perspective view of a second embodiment

D6/169; D6/191

[58] **Field of Search** D6/181, 186, 190, 167,
D6/168, 159, 160, 163, 166, 191; 211/126;
248/188.1, 174, 323; 312/108, 111

thereof;

FIG. 3 is a side perspective view of a third embodiment

of the drawer unit; and

FIG. 4 is a side perspective view of a fourth embodiment

thereof.

The sides of the drawer units not shown are like the
sides shown while the backs of the drawer members are

plain and unornamented.

The dotted lines shown in FIGS. 2 and 3 are for illustrative

purposes only.
